UNITED STATES PATENT OFFICE.

EMILE COENE, OF HALEDON, NEW JERSEY, ASSIGNOR TO THE SCHWARZENBACH HUBER CO., OF WEST HOBOKEN, NEW JERSEY, A CORPORATION OF NEW JERSEY.

DESIGN FOR A TEXTILE FABRIC.

Application filed October 17, 1928. Serial No. 28,520. Term of patent 14 years.

To all whom it may concern:

Be it known that I, EMILE COENE, a citizen of the United States, residing at 160 Pompton Road, Haledon, in the county of Bergen and State of New Jersey, have invented a new, original, and ornamental Design for Textile Fabric, of which the following is a specification, reference being had to the accompanying drawing, forming part thereof.

The figure is a representation of a textile fabric showing my new design and illustrating a single repeat unit which is continued throughout the extent of the fabric.

I claim:

The ornamental design for a textile fabric as shown and described.

EMILE COENE.
